(57) CLAIM

The ornamental design for a medicine cup, as shown and described.

DESCRIPTION

FIG. 1 is a top-front perspective view of a medicine cup showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a front-top perspective view thereof, wherein the cup portion of the medicine cup is shown removed from the base portion of the medicine cup.
The broken lines shown in the drawings illustrate portions of the medicine cup and form no part of the claimed design.

1 Claim, 8 Drawing Sheets(56)
